UNITED STATES PATENT OFFICE.

JAMES W. RIDDLE, OF PRINCETON, ILLINOIS.

CAR-COUPLING.

SPECIFICATION forming part of Letters Patent No. 549,935, dated November 19, 1895.

Application filed October 24, 1894. Serial No. 526,813. (No model.)

To all whom it may concern:

Be it known that I, JAMES W. RIDDLE, a citizen of the United States, residing at Princeton, in the county of Bureau and State of Illinois, have invented certain new and useful Improvements in Car-Couplings; and I do declare the following to be a full, clear, and exact description of the invention, such as will enable others skilled in the art to which it applies to make and use the same, reference being had to the accompanying drawings, and to the letters and figures of reference marked thereon, which form a part of this specification.

My invention relates to car-couplers. Its object is to provide a device of this character which shall be entirely automatic in its action.

The invention consists of a draw-bar having an upwardly-projecting tongue or hook, and a link having a transverse bar at one end adapted to support the link in an upright position, so that the concussion, as the cars to be coupled come together, will throw the link forward and over the corresponding hook upon the draw-bar of the other car.

It consists, further, of the peculiar form of the link, and of a gravity-latch for preventing the accidental disengagement of the link, and of such other parts and arrangement of parts as are hereinafter described.

In the accompanying drawings, Figure 1 is a plan view of a pair of draw-bars, showing my invention. Fig. 2 is a vertical longitudinal section of the same on the line 2 2 of Fig. 1. Fig. 3 is a plan view of the link. Fig. 4 is a plan section on the line 4 4 of Fig. 2. Fig. 5 is a view similar to Fig. 1, showing a modified form of construction. Fig. 6 is a vertical longitudinal section on the line 6 6 of Fig. 5. Fig. 7 is an end elevation of the draw-bar, the link being in section. Fig. 8 is a plan view of a modified form of link.

At 1 2 are shown a pair of draw-bars exactly alike in every particular and in the relative position which the draw-bars of adjacent cars in a train occupy. The lower portion of the draw-bar extends forwardly, and its upper surface is flat, forming a level table, at the sides of which are vertical flanges 5 6, which may, as shown, taper downwardly to-

ward the outer end of the bar. Projecting upwardly and centrally from the forward end of this table is a tongue or hook 3 4, which, as shown, is a separate piece of metal set into a suitable recess in the draw-bar and secured by a transverse bolt 3^a 4^a, though it is obvious that the tongue and draw-bar may be cast integrally. The inner or rearward face of the tongue 3 4 is inclined backwardly and upwardly and is preferably slightly concave, as shown.

The link X is of the ordinary form, except that one of its ends is in the form of a straight transverse bar Y, whose ends y y project beyond the sides of the link. The length of the bar Y is such that it is adapted to fit loosely between the flanges 5 5 or 6 6, thereby preventing material lateral play of the link. The bar Y being straight, the link is adapted to swing vertically upon it as it rests upon the table of the draw-bar.

At the rearward end of the table of the draw-bar a transverse abutment 7 8 rises vertically and is such distance back of the tongue 3 4 that ample space is provided for the entry of the link and to provide for the necessary longitudinal play of the link essential to the proper handling of the train. The rearward side of the abutment 7 8 and the top of that portion of the draw-bar lying behind it are adapted to the beam ordinarily lying across the end of the car.

The abutment 7 8 is vertically apertured or slotted, and within this slot is pivoted a gravity-latch 9 10, adapted normally to hang over the space between the abutment and the tongue 3 4, its end being at such altitude as to clear the link. An arm 11 12 extends upwardly from the latch 9 10 for convenience in withdrawing the latch for the purpose of uncoupling the cars. The counterweight of the latch is in the form of a rearwardly-extending arm 9^a 10^a, housed within a suitable aperture within the body of the draw-bar and being curved downwardly, so as to strike the floor of this aperture and thus limit the forward movement of the latch. The lower end of the latch 9 10 is beveled backwardly, so that the longitudinal play of the link does not tend to open or throw back the latch.

The bar Y, forming one end of the link, is provided with a tail piece or stem Z, project-

ing backwardly and longitudinally with reference to the body of the link and along its median line. The outer end of this stem is curved so that as the link lies in the position 5 it assumes in service this stem projects downwardly, a suitable aperture being provided in the draw-bar to accommodate it.

When the link X is in its upright position, as indicated by dotted lines, Fig. 2, the outer 10 end of the stem Z projects beyond the end of the draw-bar, and I prefer to provide it with a lateral projection z, which shall extend above the lower line of the draw-bar, so that as the cars come together this projection will be 15 struck by the draw-bar of the other car, thereby throwing the link down.

The aperture provided for the stem Z is of such width as to admit of very slight lateral play of the stem, thereby guiding the link 20 and insuring its engagement with the hook or tongue of the approaching car. The inner end of the aperture within which the stem Z is located is curved to correspond with the curvature of the stem, so that should the link 25 be accidentally thrown down before the cars come together the contact of the approaching draw-bar with the outer end of the link will force the stem Z against this curved wall, which will act as a cam and raise the outer 30 end of the link so as to facilitate its engagement with the hook or tongue. The rearward end of the arm 9^a 10^a is in Y form, so as to straddle this aperture. The outer or forward face of the tongue 34 is inclined backwardly, 35 so that the link, if down as the cars come together, will slide up this inclined face, which may start from a point below the surface of the table, as shown in the drawings.

The space between the tongue 34 and the 40 abutment 7 8 being greater than the thickness of the link, the latter, when in its upright position and resting against the tongue, is inclined slightly backward, resting against the top of the abutment. When in this position, however, the link is so evenly balanced 45 that a very slight concussion will throw it down, and in practice it will not be necessary, ordinarily, to use the extension z at the end of the stem Z.

50 The stem 11 12 of the latch 9 10 is provided with a radial flange 11^a 12^a immediately above the abutment 7 8, thereby preventing dirt from falling into the aperture within which the latch is pivoted.

55 The stem Z may, if desired, be wholly dispensed with, giving the link the form shown in Fig. 8, and in that event the aperture in the draw-bar provided for this stem becomes unnecessary, as shown in Figs. 5 and 6.

60 It will be seen that in practice it will be wholly unnecessary for the brakeman to manipulate the coupling as the cars come together. By being sure that there is a link in one of the draw-bars only, and especially 65 by placing the link in its upright position, he may be certain that the coupling will be

effected by the concussion as the cars come together.

The link is of such form that a car provided with my coupling is adapted to be coupled up 70 with cars provided with the prevailing style of link-couplings without change or additional appliances.

I claim as my invention—

1. In a car coupler, the combination with a 75 draw-bar having a flat upper face, a transverse abutment at the rear of the face, a hook or tongue projecting upwardly from such face in advance of and spaced apart from the transverse abutment, and an abutment rising 80 at each side of such face between the transverse abutment and the hook, of an oblong link having one of its ends prolonged beyond its sides and adapted to fit between the side abutments of the draw-bar, the whole being 85 so constructed and arranged that the link will stand upon its prolonged end behind the hook, and be thrown forward by the impact of the cars, substantially as described and for the 90 purpose set forth.

2. In a car coupling the combination with a draw bar having its upper surface of its outer end flat and provided with an upwardly projecting tongue or hook and a vertical aperture back of the hook, with an oblong link 95 having one of its ends in the form of a straight bar, and a curved guide stem projecting from such bar adapted to rest and turn upon the upper surface of the draw-bar and adapted to slide within the aperture of the draw-bar. 100

3. In a car coupling the combination with a draw bar, having the upper surface of its outer end flat and flanked by vertical flanges, and a tongue or hook projecting upwardly from this flattened surface, of an abutment 105 back of and spaced apart from the hook, the abutment and draw-bar being vertically apertured, and an oblong link having one of its ends in the form of a straight bar adapted to enter the space between the hook and the 110 abutment and having a curved guide stem projecting from such bar and adapted to slide in the aperture of the draw bar and abutment, whereby the link may stand loosely upon the draw-bar and fall forwardly, turning upon its 115 straight end and guided by its stem.

4. In a car coupling the combination with a draw bar having an upwardly projecting tongue or hook and an aperture behind the hook having its rearward wall backwardly 120 and downwardly inclined, of a link for engaging the tongue and adapted to co-operate with another similar draw-bar and having a curved stem adapted to the aperture whereby pressure upon the outer end of the link causes it 125 to be tilted upwardly.

In testimony whereof I affix my signature in presence of two witnesses.

JAMES W. RIDDLE.
